UNITED STATES PATENT OFFICE.

ALFRED SHEDLOCK, OF JERSEY CITY, NEW JERSEY.

PROCESS OF PREPARING WRAPPERS.

SPECIFICATION forming part of Letters Patent No. 764,210, dated July 5, 1904.

Application filed October 1, 1902. Serial No. 125,506. (No specimens.)

To all whom it may concern:

Be it known that I, ALFRED SHEDLOCK, a citizen of the United States, residing at Jersey City, county of Hudson, and State of New Jersey, have invented certain new and useful Improvements in Processes of Preparing Wrappers, fully described and represented in the following specification and the accompanying drawings, forming a part of the same.

10 In the manufacture of cigars it is desirable that the wrapper fit the bunch closely and accurately, and particularly that no crevices or openings be left along the overlapping lines of the wrapper which produce what is known 15 in the art as "aprons." These aprons not only disfigure the cigar, but interfere with its draft. A cigar-wrapper consists of a thin flat section of leaf cut to a proper shape, and in placing it upon a cigar it is customary to 20 strain it about the bunch, so that it may fit the bunch snugly and also take the shape of the bunch.

The present invention has for its object 25 to improve cigar-wrappers by giving them approximately the shape of the bunch prior to winding them thereupon; and the invention consists in a certain process of preparing wrappers and applying them to cigars or other analogous articles, as will be hereinafter described and then more fully pointed out in the claims hereunto appended.

In order that the invention may be fully understood, it will be explained in connection with the accompanying drawings, in which—

30 Figure 1 indicates a former with a cigar-wrapper partially applied thereto. Figs. 2 and 3 represent different modes of transferring the wrapper from the former to the bunch; and Figs. 4 and 5 are end views of 40 Figs. 2 and 3, respectively.

Referring to the drawings, 1 indicates a former, which, as shown, corresponds in shape to that shape of cigar which is ordinarily known to the trade as a "perfecto." The shape of the 45 former will, however, vary according to the particular shape of cigar or other article to which the wrapper is to be applied, and it will be further understood that the former

need not correspond exactly to the shape of the article to be wrapped. 50

In carrying out the process the wrapper, which is indicated at 2, is first shaped by winding it tightly about the former, the wrapper being thus stretched so that it corresponds to the shape of the former. After the wrapper has been given a set it is rolled from the former onto the bunch. According to the preferred mode of carrying out the invention the wrapper will be transferred from the former to the bunch, as indicated in Figs. 2 and 4—that is to say, it will be so wound about the bunch that that side of the wrapper which is outermost upon the former will form the outside of the wrapper when it is applied to the bunch. The wrapper may, however, be wound on the bunch, as indicated in Figs. 3 and 5—that is to say, that side of the wrapper which is outermost on the former forming the inside of the wrapper when it is applied to the bunch. 70

While the process which has been described is especially applicable to preparing wrappers for cigars, it might be used in preparing wrappers for other analogous articles when it is desired that the wrapper shall snugly fit the article to which it is to be applied. 75

What is claimed is—

1. The process of wrapping cigars and analogous articles which consists in winding the wrapper under tension about a former and then winding the wrapper to the article, substantially as described. 80

2. The process of wrapping cigars and analogous articles which consists in winding the wrapper under tension about a former which corresponds in shape to the article to which the wrapper is to be applied and then winding the wrapper to the article, substantially as described. 85

3. The process of wrapping cigars and analogous articles which consists in winding the wrapper under tension about a former and then winding the wrapper to the article with the same side out which was outermost on the former, substantially as described. 90

4. The process of wrapping cigars and anal-

ogous articles which consists in winding the wrapper under tension about a former which corresponds in shape to the article to which the wrapper is to be applied and then winding the wrapper to the article with the same side out which was outermost on the former, substantially as described.

5. The process of preparing a cigar-wrapper which consists in shaping the wrapper on a former which approximately corresponds

to the configuration of the cigar to which the wrapper is to be applied, substantially as described.

In testimony whereof I have hereunto set my hand in the presence of two subscribing witnesses.

ALFRED SHEDLOCK.

Correction in Letters Patent No. 764,210.

It is hereby certified that Letters Patent No. 764,210, granted July 5, 1904, upon the application of Alfred Shedlock, of Jersey City, New Jersey, for an improvement in "Processes of Preparing Wrappers," was erroneously issued to said "Shedlock" as owner of said invention; whereas the said Letters Patent should have been issued to *The American Tobacco Company, of New York, N. Y.*, a corporation of New Jersey, as owner of the entire interest in said invention, as shown by the assignments of record in this office; and that the said Letters Patent should be read with this correction therein that the same may conform to the record of the case in the Patent Office.

Signed and sealed this 16th day of August, A. D., 1904.

E. B. MOORE,
Acting Commissioner of Patents.

ogous articles which consists in winding the wrapper under tension about a former which corresponds in shape to the article to which the wrapper is to be applied and then winding the wrapper to the article with the same side out which was outermost on the former, substantially as described.

5. The process of preparing a cigar-wrapper which consists in shaping the wrapper on a former which approximately corresponds

to the configuration of the cigar to which the wrapper is to be applied, substantially as described.

In testimony whereof I have hereunto set my hand in the presence of two subscribing witnesses.
